UNITED STATES PATENT OFFICE.

HARRISON D. BULLARD, OF NASHVILLE, TENNESSEE.

PUZZLE OR TOY.

No. 913,689.

Specification of Letters Patent.

Patented March 2, 1909.

Application filed April 9, 1908. Serial No. 426,061.

To all whom it may concern:

Be it known that I, HARRISON D. BULLARD, a citizen of the United States, residing at Nashville, in the county of Davidson and State of Tennessee, have invented a new and useful Improvement in Puzzles or Toys, of which the following is a specification.

This invention relates generally to toys, and more particularly to a figure toy involving in its construction a puzzle.

The object of the invention is to provide an exceedingly simple and inexpensive construction of toy puzzle which besides affording amusement and entertainment, can be used for advertising purposes.

Broadly speaking the invention comprises an animal figure cut from a piece of cardboard or other suitable material and having an aperture in the head, and also an aperture 20 at the end of each fore-leg, a string or cord adapted to be passed through said apertures in a definite manner, one end of the string having a ring permanently connected thereto, the opposite end of the string having a 25 ring detachably connected thereto, the solution of the puzzle being to disconnect the cord from the figure and incidentally detach the detachable ring.

The invention consists also in certain 30 tails of construction hereinafter fully described and pointed out in the claims.

In the drawings forming a part of this specification:—Figure 1 is a view of a puzzle constructed in accordance with my invention, the cord and rings being arranged for the solution of the puzzle. Fig. 2 is a view showing the first step toward the solution, and Figs. 3, 4, 5, and 6 are similar views illustrating the further steps and the final 40 solution of the puzzle.

In carrying out my invention I employ an animal figure A which is preferably made of card-board or any other suitable material and it will of course be understood that this 45 figure can be made any size desired and it will also be understood that although I have shown my invention applied to a toy bear; it can be applied equally as well to any other figure having a head and fore-legs, and in 50 some instances a human figure may be employed, utilizing the arms in place of the fore-legs. An opening B is produced in the nose of the bear, and an opening C in the end of one fore-leg and an opening D in the end 55 of the other fore-leg.

E indicates a cord or string which is passed through the opening C and D, looped and fastened in the opening B as shown in Fig. 1, and has a ring F permanently attached at one end of the string and a ring G connected to the other end by means of a slip-loop H and it will be noted that this ring G is somewhat larger than the ring F.

It will be understood that the openings B, C and D may be reinforced by means of eyelets to prevent wear.

The puzzle as before stated is to manipulate the string and ring as to remove the string from the nose and legs and also disconnect the detachable ring from the string. To remove the string the loop I is slackened and passed through the hole D, and slipped over the ring G as most clearly shown in Fig. 2, and by pulling upon the string, the loop will be drawn back through the ring D 75 and out of the opening B as most clearly shown in Figs. 3 and 4. The string is therefore released from the nose. Now, take the small loop H at the end of the string where it is looped to the ring G and pass it through the openings D and C, as shown in Fig. 5, and then put the small ring F through this loop and this will release the large ring G 80 and the string can be drawn out through the opening B and C. To put the string back 85 run it through the openings C and D and the ring G as shown in Fig. 6 and then reverse the order of operation, hereinbefore described and the string will first be arranged in the paws with the rings at each end and then the loop will be fastened in the nose as most clearly shown in Fig. 1.

Having thus fully described my invention, what I claim as new and desire to secure by Letters Patent is:—

1. A puzzle comprising a body portion 95 representing an animal and having a head and two members, said head and members being apertured, and a string passing through said apertures and carrying a ring at each 100 end, as set forth.

2. A puzzle comprising a body portion representing an animal and having a head and two members, said head and members being apertured, a string passing through 105 said apertures and having a ring permanently connected to one end and a ring detachably connected to the opposite end of the string.

3. A puzzle comprising a body portion representing an animal and having a head 110

and two members, said head and members being apertured, a string adapted to be passed through the members and fastened to the head by means of a slip loop, a ring 5 permanently connected to one end of the string and a second ring connected to the opposite end of the string by means of a slip-loop.

4. A puzzle comprising an animal figure, 10 the head and fore-legs of which are aper-

tured and a string adapted to be passed through said apertures, and connected to the head, and a ring connected to one end of the string, and a second ring detachably connected to the opposite end of the string.
